D. 386,671 11/1997 Park ..... D9/305*Primary Examiner*—James Gandy*Assistant Examiner*—Cathron B. Matta*Attorney, Agent, or Firm*—Finnegan, Henderson, Farabow, Garrett & Dunner L.L.P.[57] CLAIM

The ornamental design for a portion of a confectionary package, as shown and described.

DESCRIPTION

The sole FIGURE is a top plan view of a portion of a confectionary package embodying my design.

The portion of the confectionary package is of no appreciable thickness and the undisclosed bottom plan view is unornamented.

The broken lines which define the bounds of the claimed design form no part thereof.
